UNITED STATES PATENT OFFICE.

LOUIS B. GOLDBERG, NATHAN GOLDBERG, JACOB M. GOLDBERG, AND WILLIAM GOLDBERG, OF DENVER, COLORADO.

CAMP-STOVE CASING.

Application filed November 26, 1921, Serial No. 517,903. Renewed February 9, 1924.

To all whom it may concern:

Be it known that we, LOUIS B. GOLDBERG, NATHAN GOLDBERG, JACOB M. GOLDBERG, and WILLIAM GOLDBERG, citizens of the United States, and residents of the city and county of Denver, State of Colorado, have invented certain new and useful Improvements in Camp-Stove Casings, of which the following is a description in such full, clear, and 10 exact terms as will enable others skilled in the art to make and use the same, reference being had to the accompanying drawings, forming a part hereof.

The object of the invention is to provide 15 a device of the class stated which shall fold up into compact form when not in use, special reference being had to externally projecting parts and more particularly the legs or supports for the stove.

20 The stove comprises a case which carries the various parts, and a cover therefor, and the invention resides more particularly in the following features: a clip hinged directly to the edge of the cover and adapted 25 to spring over a bead on the case to retain the cover, a jointed projecting valve adapted to fold into the case through a slot therein, and a pair of legs or supports of angular formation having projecting ground engaging 30 portions with a portion hinged to the casing on one side of each projection and a portion to engage the casing on the other side thereof whereby the ground engaging portions may be swung out of the way along 35 the sides of the casing.

In the drawings wherein certain embodiments of the invention are disclosed:

Fig. 1 is a plan with a part of the casing walls and most of the cover broken 40 away;

Fig. 2 is an end elevation of the casing;

Fig. 3 is a horizontal sectional detail on line 3—3 of Fig. 2;

Fig. 3^a is a sectional detail on line 3^a—3^a 45 of Fig. 3.

Fig. 4 is a sectional detail on line 4—4 of Fig. 1;

Fig. 5 is a perspective view of the casing and parts;

Fig. 6 is an elevational detail showing the legs of Fig. 5 in folded position;

Fig. 7 is an elevational detail showing a different leg arrangement;

Fig. 8 is a detail showing a further slight modification.

The casing 10 has a cover 12 secured thereto as by means of hinges 14 and adapted to be retained in closed position as by means of a clip 15. The clip 15 is mounted upon the cover by means of an eye 16 wrapped around a rod 18 forming the bead of the cover, and the other end of the clip is provided with a curved detent 20 adapted to snap over the bead 21 formed by a rod or wire 22 on the casing. This forms a positively acting simple retainer.

One end of the casing 10 is provided with a T-shaped slot, the stem 24 of which receives the shank 25 of a valve for a burner B, while the cross portion 26 thereof is 70 adapted to receive the head 28 of the valve stem when the outer portion thereof is swung upon the pivot 30 at an intermediate point in said stem. A sleeve 32 is adapted to be slid over the joint 30 to prevent 75 bending thereof when desired to operate the burner, and to be withdrawn from the joint into position against head 28 when desired to move the projecting part of stem 25 and head 28 into position within the casing as 80 indicated in dotted lines in Fig. 3. The inner end of stem 25 is threaded to enter the burner B as at 34. Thus, when the stove is to be moved or packed, the sleeve 32 is withdrawn and the projecting portions 85 swung through T-slot 24, 26 to protected position within the casing.

The stove casing is supported by means of legs which are, as shown, generally V-shaped. Each leg or support has a middle 90 cross bar adapted to engage the bottom of the case when in operative position, this bar being indicated at 40, while the ends of the rod which form each leg are offset at 42 to provide pivots on the casing. The bar 40 95 is connected with each pivot 42 by a short leg 44 adjoining the bar and a longer leg 45 adjoining the pivot, the apex 46 at the junction of the two legs being adapted to rest upon the ground when in operative 100 position and to lie along the side of the casing when folded up to inoperative position.

In all forms the bar 40 of each support engages the bottom of the casing when in operative position. In the form of Figs. 5 105 and 6, the pivots 42 are spaced somewhat

from the ends of the casing, so that when in operative position the bars 40 engage the bottom adjacent the ends and when in inoperative position they engage the bottom 5 on the opposite sides of the pivots 42. In the forms of Figs. 7 and 8, the pivots are adjacent the ends of the casing, so that bars 40 engage the bottom at a point spaced in each instance from the respective end when 10 in operative position. With the form of Fig. 7, the support is moved to inoperative position by swinging it around the corner of the casing and bringing the bar 40 into engagement with the end thereof at a point 15 slightly below the bead 21. With the form of Fig. 8, the support is also swung around the corner of the casing, but the parts are so proportioned that the bar 40 swings under slight tension over a curved lip or rib 20 112 on the end of the cover 12 and snaps behind the elevation of the rib or lip to retain the cover and thereby make elimination of the clip 15 of Figs. 1 and 4 possible, although clip 15 may be retained if 25 vantageous or desirable.

It is obvious that swinging of the leg portions 44, 45 along the sides of the casing to inoperative position is due to an extension of said portions beyond the sides of the 30 casing sufficient to permit the movement.

From the foregoing it will be seen that we have devised a simple and cheap construction, a neat and compact exterior, and simple means for retaining the assembly of 35 a camp stove for storage or transport.

We claim:

1. A casing and supports pivoted thereon, said supports including pivoting parts, a spaced casing-engaging bar for engaging 40 the bottom of the casing when supporting the same and projecting legs at opposite ends of said bar adapted to be swung along the sides of the casing into retracted position.

2. A casing having sides and an end, a support thereon pivoted thereto adjacent said end, said support comprising pivots, a bar spaced from said pivots and adapted to engage the bottom of the casing to support 50 the same when in operative position, and projecting leg members connecting said bar and said pivots and adapted to be swung out of the way along said sides of the casing.

3. A stove casing and supports thereon, 55 each support having a pivotal connection with opposite sides of the casing, a bar spaced from the pivots and adapted to engage the casing on either side of the pivots, and leg members connecting the ends of 60 each bar with the pivots thereof, said leg members projecting from the pivots and the bar to engage a supporting surface and adapted to be swung along said sides of the casing into withdrawn position.

4. A casing, and a support movable there-

on, said support having pivotal connection at the opposite sides of the casing, a bar spaced from the pivots to engage across the bottom of the casing, a leg member at each side of the casing connecting the respective 70 pivot and the respective end of the bar and adapted to project from the bottom to engage a surface, said leg members lying beyond the sides of the casing so as to be swung alongside thereof to withdrawn position. 75

5. In a camp stove, a valve stem, a casing from which said stem projects, and means within the casing for operation by said stem, said casing having a slot, said stem 80 being jointed so as to swing the projecting end of the stem through said slot and into the interior of the casing.

6. In a camp stove, a casing having a T-shaped slot, and a headed stem projecting 85 through said slot and beyond the casing, said stem having a joint within the casing whereby the projecting portion and said head may be swung through said slot into the casing. 90

7. In a camp stove, a casing having a slot, a valve stem projecting through said slot outside the casing, a member within the casing for control by said stem, said stem having a joint to permit the folding of the 95 projecting portion of the stem through the casing to protected position within the casing, and a member slidably over said joint to prevent bending thereof.

8. In a camp stove, a casing, a bead on the 100 upper edge thereof, a cover on the casing, a rod on the edge of the cover, and a clip pivoted on said rod and having a detent to snap over the bead on the casing to retain the cover in closed position. 105

9. In combination, a casing and a supporting leg pivoted thereon, said leg comprising a rod having its ends opposed and pivoted on the casing while its middle portion is in the form of a bar adapted to engage the 110 bottom of the casing, the pivots and the bar being in substantially the same plane, and offset ground engaging members extending from said plane and connecting the pivots with the bar, said members lying 115 sufficiently beyond the sides of the casing to be swung into withdrawn position along the sides of the casing.

10. A casing and supports pivoted thereon, said supports comprising a bar having 120 a straight central portion adapted to engage the bottom of the casing when supporting the same, and projecting legs at opposite ends of said bar adapted to be swung along the sides of the casing into retracted position. 125

11. A casing and supports pivoted thereon, said supports comprising a bar having a straight central portion, the ends of said bar being bent to lie in a plane substan- 130

tially perpendicular to said straight central portion which is adapted to engage the bottom of the casing, said bent ends forming legs adapted to be swung along the sides to engage the bottom of the casing, said end portions being bent to form legs adapted to be swung along the sides of the casing into retracted position.

5 of the casing into retracted position.

12. A casing having sides and a bottom portion, a support pivoted thereon, said support comprising a straight bar having its ends bent so as to lie in planes at right

10 angles to the straight bar which is adapted

to engage the bottom of the casing, said end portions being bent to form legs adapted to be swung along the sides of the casing into retracted position.

In testimony whereof, we affix our sig- 15 natures.
